HORACE H. BURDETT, OF HOPEDALE, MASSACHUSETTS, ASSIGNOR TO DRAPER CORPORATION, OF HOPEDALE, MASSACHUSETTS, A CORPORATION OF MAINE.

FILLING END CONTROLLER FOR REPLENISHING LOOMS

Application filed July 15, 1930. Serial No. 468,012.

This invention relates to filling replenishing looms wherein a fresh supply of filling is transferred to the shuttle when that previously in use has become substantially but 55 not entirely exhausted.

When replenishment of filling is effected by the transfer of a fresh filling carrier into the shuttle and the ejection of the spent filling carrier, there is an end of filling extending 10 longitudinally of the shuttle box through the eye of the shuttle to the spent filling carrier or bobbin and unless this filling end is completely removed and held in removed position from the shuttle box, such filling end may 15 be drawn into the shed by the picking movement of the shuttle or may be placed in the danger zone of such defective operation by the air currents induced by the lay movements.

20 Much attention and skill have been devoted to the removal of the spent filling end and it has been proposed heretofore to part and clamp the filling end adjacent the shuttle eye and withdraw the filling from the shuttle box frontwardly, but the light and fugitive 25 character of the filling end sometimes renders the withdrawing operation defective and notwithstanding that the end has been moved frontwardly from the shuttle box it will frequently either break or be caught by the lay or shuttle box parts by lay movements and finally be taken into the shed and form defective cloth.

30 Among the further difficulties encountered 35 in removing the spent filling end is the liability of the end leading along the shuttle box being clamped between the front wall of the shuttle box and the side of the shuttle when the latter is in replenishing position, 40 and these conditions may cause the spent filling end to be broken as it is withdrawn frontwardly, leaving a part to be carried into the shed.

45 One of the important features of the present invention, therefore, consists in a spent filling end controller constituted as a parter and clamp which on call for replenishment is moved rearwardly towards the shuttle box to position the parter and clamp for parting 50 and clamping the filling end close to the

shuttle eye and then withdrawing it frontwardly in an inclined path and in a direction towards the inner end of the shuttle box, the front box plate being provided with a longitudinally extending slot, open at its inner end, 55 for the free removal of the spent filling end entirely from the shuttle box.

By withdrawing the spent filling end from the shuttle in the manner above described and moving the clamped end towards the inner 60 end of the shuttle box, slack is produced in the spent filling end which facilitates its passage through the longitudinal slot in the front box plate and also enables the filling end to be caught beneath the thread catcher 65 extending frontwardly from the front box plate, so that the filling end is positively held out of the air currents produced by the moving shuttle and is prevented from being carried into the shed.

70 The invention and novel features thereof will best be made clear from the following description and the accompanying drawings of one good form of means for carrying the invention into effect.

75 In the drawings:

Fig. 1 is a plan view at the replenishing side of a loom provided with the present invention;

Fig. 2 is a front perspective view showing 80 the relation of parts when the filling end controller is in front position;

Fig. 3 is a detached detail in plan view showing the filling end controller and the inclined path of movement which is given to 85 the slide carrying the controller; and

Fig. 4 is a side elevation thereof.

The loom frame 1 may be of usual construction supporting a hopper or magazine 2 for holding the fresh filling carriers which 90 are to be transferred to the shuttle on call for replenishment of filling. As indicated in the present instance, the magazine or hopper 2 is supported by a stand 3, Fig. 1, which may be secured to the loom frame by bolts 4. 95

The lay 5 may be operated as usual from the crank shaft and at its outer end carries the replenishing shuttle box 6, and the shuttle 7 may be of usual type of filling replenishing 100 shuttles now well-known in the art.

The front shuttle box plate is provided with a longitudinally extending opening 8 which divides the front box plate into the anchoring member 9 and the shorter upper member 10 which is secured to the anchoring member 9 at the outer portion thereof, as at 11, and is solely supported by the anchoring member.

The lower flange portion of the anchoring member may be secured to the lay 5 by bolts 12 and 13 which extend through slotted lugs 14 formed in the flange of the anchoring member, with the result that while the anchoring member is rigidly secured in position, the shorter upper member 10, being supported solely at the outer portion of the anchoring member, may yield to some degree, and as the shuttle enters the replenishing shuttle box the inner face portion of the anchoring member will first engage the shuttle and resist the first impact, and thereafter the shorter upper member 10 will act upon the shuttle as it moves to picking position in the shuttle box.

Between the inner end of the anchoring member and the inner end of the shorter upper member of the front box plate there is a free and unobstructed opening which not only provides an open inner end for the front box plate but likewise presents a space into which the spent filling end may be thrown as the shuttle comes to rest.

At the inner end of the anchoring member 9 is a projection constituting a spent end catcher 15 which extends frontwardly and below the level of the lay end. A notch or hook is formed at the top portion of the projection to catch the incoming filling end should it tend to slide by the top of the box plate into the shuttle box.

When the spent filling end is withdrawn from the shuttle box, as hereinafter described, it is held in front position for several picks or until the temple thread cutter parts it at the selvage, but should the spent filling end be broken by catching on some of the lay parts before it is cut at the cloth selvage, the loose end would probably be drawn into the shed. The thread catcher of the present invention, however, avoids this objection by holding the spent filling end, which is given a certain amount of slack between the cloth selvage and the thread parter and clamp, as will appear, so that it is prevented from catching on any part of the lay or shuttle box during lay movements.

Secured to the hopper or magazine stand is a stud shaft 16 on which is mounted the transferrer 17 normally under the influence of a spring 18, as usual, for maintaining the transferrer in its upper or inoperative position.

Extending downwardly from the hub of the transferrer is an arm 19 to which is pivotally connected at 20 the usual dog 21, and extending from the dog 21 is a stud 22 which

engages the slotted arm 23 mounted for pivotal movement about the axis 24 on call for replenishment of filling, the result being that on rocking movement of the shaft 24 the dog 21 will be raised into the path of the usual bunter 25 on the lay, whereby the transferrer is operated to transfer a fresh filling carrier to the shuttle and eject the spent filling carrier or bobbin therein.

Mounted on the transferrer stud 16 at the outer end portion thereof is a bracket, the hub portion 26 of which is secured to the stud shaft 16, and extending downwardly from the hub are the arms 27 and 28 which are arranged in a vertical plane inclined rearwardly towards the outer end of the shuttle in the replenishing box.

The arms 27 and 28, being positioned as described, carry the guide 29 for a slide 30 which has a movement towards and from the front of the loom in an inclined path diverging outwardly towards the outer end of the shuttle box.

The inclined slide 30 has a laterally projecting portion 31, Fig. 3, and upon which is mounted the thread controller constituted as a thread parter and clamp having the usual cutting and clamping members. The fixed cutting member is indicated at 32 and the fixed clamping member at 33, while between the two is the movable cutting member 34 and the movable clamping member 35, which are pivoted to the projecting lug 31 as at 36, and a pin 37 connected to the movable cutting and parting members serves to actuate them as will more fully appear.

Mounted upon the transferrer stud 16 for rocking movement is the yoke 38 having the arms 39 and 40 which swing about the transferrer stud. The arm 40 is extended downwardly and is provided with a slot 41 at its lower end portion which engages a relatively long pin 42 extending laterally from the slide 30, as indicated more clearly in Fig. 3. The arm 40 which constitutes an actuator for the slide moves or swings in a vertical plane extending at right angles to the lay, while the slide 30 which is actuated by the arm 40 moves from front to rear position in an inclined path to part and clamp the filling, and as the actuator swings frontwardly in the vertical plane of its movement the slide 30 moves frontwardly in an inclined direction towards the cloth selvage or inner end of the shuttle box, with the result that on call for replenishment of filling, as will later appear, the actuator and the thread parter and clamp will cause the spent filling end to be withdrawn frontwardly from the shuttle box to provide slack between the parter and clamp and the cloth selvage so that the slack spent filling end may engage beneath the thread catcher 15 as the lay again moves frontwardly and thereafter the filling end will be prevented

positively from passing upwardly into the danger zone or shuttle path.

Extending from the yoke 38, Fig. 2, is an arm 43 the downturned end 44 of which is yieldingly connected by the link 45 with an arm 46 secured to the shaft 24 of the slotted arm 23, and since the shaft 24 is rocked on call for replenishment of filling the actuator 40 will be moved rearwardly to position the thread parter and clamp to part and clamp 10 the thread adjacent the shuttle eye, and when the shaft 24 rocks in the opposite direction after replenishment, the actuator will again be moved frontwardly in its plane of movement to withdraw the slide 30 and the thread 15 parter and clamp frontwardly in an inclined path towards the inner end of the shuttle box.

Should the spent filling end be unprovided with slack as it is drawn frontwardly from the shuttle box it is liable to catch upon the 20 upper portion of the anchoring member 9 of the front box plate or upon the stud 13 which secures the anchoring member to the lay, but by providing slack in the spent filling end as it is withdrawn from the shuttle in the inclined path described, the spent filling end 25 will engage beneath the catcher 15 and be thereafter held from moving into the path of the shuttle or the air currents produced thereby.

Mounted upon the transerrer stud 16 is a second yoke 47 mounted for rocking movement, and extending towards the inner end of the shuttle box is the arm 48 secured to 30 the yoke and likewise connected by a yielding member 49 to a stud 50 on the downwardly extending arm 19 of the transerrer. Connected to the outer end of the yoke 47 is an arm 51 in which is adjustably mounted a 35 parter and clamp closing member 52 which, when the parter and clamp are in rearward position, acts upon the pin 37 of the parter and clamp to part and clamp the spent filling.

It is desirable that the clamped end of the spent filling be held by the parter and clamp until the next call for replenishment of filling, and in order to open the parter and clamp as they move to rear position as 45 described, there is a trip opener 53 of usual construction and supported for rocking movement freely in one direction to act upon the pin 37 and cause separation of the parter and clamping members as they move to rearward position.

As the parter and clamp move to rearward position to part and clamp the spent filling end, it is desirable that they should be properly positioned in the enlarged opening 54 in the front box plate, and to this end the slide 30, which as above described, moves in an inclined direction rearwardly towards the outer end of the shuttle box and then frontwardly towards the cloth selvage or inner end of the shuttle box, is provided with

a bunter 55 which may engage a part carried by the lay and properly position the parter and clamp for their parting and clamping operations.

The movement of the parter and clamp, 70 the bunter and the slide 30 carrying these parts, is indicated by dotted lines in Fig. 1, wherein it will be noted that the parts cited move from their full line position rearwardly towards the outer end of the shuttle box 75 on call for replenishment of filling and then return in an inclined path towards the inner end of the shuttle box as they move to outer position, thereby producing slack in the 80 spent filling end.

What is claimed is:

1. In a filling replenishing loom, the combination of the lay having a replenishing shuttle box the front wall of which is provided with a longitudinal slot open at its inner end, a thread parter and clamp for parting and clamping the outgoing filling adjacent the shuttle eye of a boxed shuttle and adapted to hold the filling extending between the selvage and clamp, a slide on which the parter and clamp are mounted, a guide for the slide having its guiding portion extending between the ends of the shuttle box in a direction inclined to the longitudinal axis of the shuttle, and an actuator for moving the slide in the guide towards and from the front of the loom in a path inclined outwardly towards the end of the shuttle box to present the parter and clamp to a position adjacent the shuttle eye 100 and then remove the clamped end of the filling frontwardly in a direction inclined inwardly towards the cloth selvage to reduce the tension of the filling end and facilitate its withdrawal through said slot. 105

2. In a filling replenishing loom, the combination of the lay having a replenishing shuttle box the front wall of which is provided with a longitudinal slot open at its inner end, a thread parter and clamp for parting and clamping the outgoing filling adjacent the shuttle eye of a boxed shuttle and adapted to hold the filling extending from the selvage to the clamp, a slide on which the parter and clamp are mounted, a guide for the slide having its guiding portion extending between the ends of the shuttle box in a direction inclined to the longitudinal axis of the shuttle, an actuator for the slide, and connections between the actuator and slide permitting movement of the slide in a direction inclined outwardly towards the shuttle eye of the boxed shuttle and then in a direction inclined inwardly towards the cloth selvage as the slide is moved to its front position to thereby reduce the tension of the filling end and facilitate its withdrawal through said slot. 115

3. In a filling replenishing loom, the combination of the lay having a replenishing 120

shuttle box the front wall of which is provided with a longitudinal slot open at its inner end, a thread parter and clamp for parting and clamping the outgoing filling adjacent the shuttle eye of a boxed shuttle and adapted to hold the filling extending from the selvage to the clamp, a slide on which the parter and clamp are mounted, a guide for the slide having its guiding portion extending between the ends of the shuttle box in a direction inclined to the longitudinal axis of the shuttle, an actuator for the slide movable in a plane extending at right angles to the lay, and connections between the actuator and slide for moving the slide along its guide rearwardly in a direction inclined towards the outer end of the shuttle box and forwardly in an inclined direction towards the cloth selvage to thereby reduce the tension of the filling end and facilitate its withdrawal through said slot.

4. In a filling replenishing loom, the combination of the lay having a replenishing shuttle box, the front plate of which has a longitudinal slot open at its inner end, a spent thread catcher at the inner end of the shuttle box, a thread parter and clamp for parting and clamping the spent filling adjacent the shuttle eye and adapted to hold the filling extending from the selvage to the clamp, a slide on which the thread parter and clamp are mounted, a guide for the slide between the ends of the shuttle box inclined rearwardly towards the outer end of the shuttle box for directing the slide in an inclined path towards and from the front of the loom, and an actuator for the slide for withdrawing the spent filling end forwardly in the inclined path of the slide towards the cloth selvage to provide sufficient slack in the spent filling at the front of the shuttle box to facilitate its passage through said slot and enable the spent filling to be engaged by the thread catcher below the shuttle box.

5. In a filling replenishing loom, the combination of the lay having a replenishing shuttle box, the front plate of which has a longitudinal slot open at its inner end, a spent thread catcher at the inner end of the shuttle box, a thread parter and clamp for parting and clamping the spent filling adjacent the shuttle eye and adapted to hold the filling extending from the selvage to the clamp, a slide on which the thread parter and clamp are mounted, a guide for the slide between the ends of the shuttle box inclined rearwardly towards the outer end of the shuttle box for directing the slide in an inclined path towards and from the front of the loom, a swinging actuator for the slide mounted for movement in a plane at an angle to the plane of movement of the slide, and an elongated pin connection between the swinging actuator and slide for withdrawing the spent filling end forwardly in the inclined path of the

guide towards the cloth selvage to provide slack in the spent filling that it may be drawn freely through said slot and engaged below the thread catcher to prevent it from being drawn into the shed.

6. In a filling replenishing loom, the combination of the lay having a replenishing shuttle box, the front plate of which is provided with a longitudinal slot which divides the front plate into an anchoring member extending the length of the shuttle box and a shorter upper member supported solely by the anchoring member at the outer portion thereof that an open space may be provided between the inner ends of the two members, a thread parter and clamp adapted to hold the filling extending between the selvage and clamp, an inclined guide for directing the parter and clamp towards the outer end of the shuttle box to part and clamp the spent filling adjacent the shuttle eye and then forwardly in a path inclined inwardly towards the cloth selvage to reduce the tension of the filling so that the spent filling end may be withdrawn forwardly from between the anchoring and shorter upper members of the front box plate and produce sufficient slack in the filling to cause it to drop below the shuttle box.

7. In a filling replenishing loom, the combination of the lay having a replenishing shuttle box, the front wall of which is provided with a longitudinal slot open at its inner end, a thread parter and clamp for parting and clamping the outgoing filling adjacent the shuttle eye of a boxed shuttle and adapted to hold the filling extending from the selvage to the clamp, a slide on which the parter and clamp are mounted, a guide for the slide having its guiding portion extending between the ends of the shuttle box in a direction inclined to the longitudinal axis of the shuttle, a rocking yoke, means for rocking the same to actuate the slide so that it moves rearwardly in a direction inclined outwardly towards the shuttle eye of the boxed shuttle and forwardly in a direction inclined inwardly towards the cloth selvage to reduce the tension upon the filling, and a closing member secured to said yoke and actuated by the yoke movement to close the parter and clamp.

In testimony whereof, I have signed my name to this specification.

HORACE H. BURDETT.
